UNITED STATES PATENT OFFICE.

ARTHUR S. FORD, OF NEW YORK, N. Y.

FRAME.

1,331,009.

Specification of Letters Patent. Patented Feb. 17, 1920.

Application filed February 12, 1919. Serial No. 276,527.

To all whom it may concern:

Be it known that I, ARTHUR S. FORD, a citizen of the United States, and a resident of New York, in the county of New York 5 and State of New York, have invented a certain new and useful Improvement in Frames, of which the following is a full, clear, and exact specification.

This invention relates more particularly 10 to a class of picture frames and the like.

My invention has for its object primarily to provide a frame designed to be employed for displaying on walls and elsewhere the pictures of objects, advertising and other 15 subject matters in an unusually attractive manner, and which is adapted to be made of cardboard or other inexpensive pliable material in a knockdown form to allow of being transported in large quantities in a 20 compact parcel as well as allowing of being easily assembled for use. The invention contemplates the formation of the frame from a sheet of pliable material which is cut to provide a blank consisting of an angular 25 backing or surface element on which the subject matter for display is mounted or printed or otherwise inscribed. Extension members protrude laterally from the surface element, and these extension members 30 are adapted to be folded to provide on one face of the surface element, at its marginal edges a frame bar of approximately an inverted U-shape in cross section. Through the surface element in spaced proximity to 35 two of its opposite extension members may be two pairs of spaced slots, and projecting from each of these extension members, may be a tongue adapted to be inserted in the slots of each pair whereby the frame bar will be 40 releasably locked to the surface element.

With these and other objects in view the invention will be hereinafter more particularly described with reference to the accompanying drawing forming a part of this 45 specification in which similar characters of reference indicate corresponding parts in all the views, and will then be pointed out in the claims at the end of the description.

In the drawing, Figure 1 is a top plan of 50 a form of pliable blank from which my improved frame is formed.

Fig. 2 is a fragmentary perspective view showing part of the frame when folded.

Fig. 3 is a perspective view of the frame 55 when formed by folding the pliable blank.

Fig. 4 is a detail sectional view taken on the line 4—4 of Fig. 3, and

Fig. 5 is a detail sectional view taken on the line 5—5 of Fig. 3.

The device or frame may be made from a 60 foldable blank, as 10, cut from any suitable pliable material, such as cardboard, heavy paper, thin sheet metal or the like, and this blank has a backing or surface element, as 11, which may be of any desired angular 65 shape, though the form of the surface element illustrated is substantially square or rectangular. The marginal edges of the rectangular surface element are provided by scoring, as at 12, 13, 14, 15, the central part 70 of the blank, and projecting in opposite lateral directions from the scoring 12 and 14 of the surface element are two extension members or flaps, as 16 and 17, respectively. Both of the extension members 16 and 17 are 75 substantially rectangular of lengths corresponding to the length of the surface element, while being considerably narrower than the surface element. The extension member 16 is scored lengthwise, as at 18, in 80 spaced proximity to the scoring 12, and this member is also scored, as at 19, in spaced proximity to its free edge. The extension member 17 is likewise scored lengthwise, as at 20, in spaced proximity to the scoring 14, 85 while in spaced proximity to its free lengthwise edge is another scoring, as 21. Protruding in opposite lateral directions from the respective scorings 13 and 15 of the surface element 10 are two more extension members or flaps 22 and 23 each of which have 90 tapered or converging ends, as 24 and 25. The extension member 22 is scored lengthwise, as at 27, in spaced proximity to the scoring 15, and in spaced proximity to its free end this member is scored lengthwise, as at 28. The extension member 23 is likewise scored lengthwise, at 29, in spaced proximity to the scoring 15, and in spaced proximity to its free end this member is scored lengthwise, as at 30. Extending outwardly from the extension member 22 is a tongue, as 31, while extending outwardly from the extension member 23 is another tongue 32. At the juncture of the extension member 22 with the tongue 31 is a crosswise scoring 33, and in spaced proximity to the free end of this tongue is a second crosswise scoring 34. At the juncture of the extension member 23 with the tongue 100 32 is a crosswise scoring 35, and in spaced proximity to the free end of this tongue is a second crosswise scoring 36. At the juncture of the extension member 23 with the tongue 110 36 is a crosswise scoring 37, and in spaced proximity to the free end of this tongue is a second crosswise scoring 38.

32 is a crosswise scoring, as 35, while in spaced proximity to the free end of this tongue is another crosswise scoring 36. The tongues 31 and 32 are preferably somewhat narrower than the extension members 22 and 23, and in the surface element 11 at the scoring 13 is a pair of spaced slots 37 of lengths adapted to freely receive the tongue 31, while in the surface element 11 at the scoring 15 is 10 a pair of spaced slots 38 of lengths adapted to freely receive the tongue 32. Projecting in opposite lateral directions from the ends of the extension member 16 adjacent to and extending toward the extension members 22 15 and 23 may be fingers 39 and 40 which are of widths slightly less than the widths of the parts of the extension members 22 and 23 between the scorings 13, 27 and 29, 30. Projecting in opposite lateral directions from 20 the ends of the extension member 17 also adjacent to and extending toward the extension members 22 and 23 may be two more fingers 41 and 42 of widths similar to the widths of the fingers 39 and 40.

25 To fold the blank 10 for forming the frame the extension member 16 is bent lengthwise at the scorings 12, 18, 19 and the member is folded upon the surface element or backing 11 in somewhat the fashion of an inverted **U** in cross section, the fold at the free edge of the member being inturned so as to lay upon the surface member. The extension member 17 is likewise bent lengthwise at the scorings 14, 20, 21 and this member is folded upon one face of the surface element or backing 11 also in somewhat the fashion of an inverted **U** in cross section. With this arrangement of the extension members 16 and 17 the fingers 39, 40, 41, 42 30 are bent upwardly at right angles toward these members, and the fingers are then disposed edgewise upon the extension members or flaps 22 and 23. Following this disposition of these parts of the blank, the extension member 22 is bent lengthwise at the scorings 27 and 28, and the tongue 31 is bent lengthwise at its scoring 34. The extension member 23 is similarly bent lengthwise at its scorings 29 and 30, while the tongue 32 35 is bent lengthwise at its scoring 36. Both of the extension members 22 and 23 are then folded upon the surface element 11 in somewhat the fashion of an inverted **U** in cross section as well as being folded to inclose the fingers 39, 40, 41, 42. The bent tongue 31 is guided downwardly through one of the slots 37 and then guided upwardly through the second one of these slots so that the free end of the tongue will be disposed in the 40 **U**-shaped extension member 22, and the bent tongue 32 is also guided downwardly through one of the slots 38 and then directed upwardly through the second slot of the pair

38 so that the free end of the tongue will be within the **U**-shaped extension member 23. 65 Thus I provide a very simple and efficient frame designed to be used for displaying on walls and elsewhere pictures of objects and other subject matters, and which is of a knockdown type for being folded into an assembled form when it is desired to use the frame. In order to allow the frame to be hung on one or more nails or the like in the surface element or backing 11 at spaced parts of its marginal edges may be provided 70 a number of holes, as 43 and 44.

75 In the foregoing description I have embodied the preferred form of my invention, but I do not wish to be understood as limiting myself thereto, as I am aware that modifications may be made therein without departing from the principle or sacrificing any of the advantages of this invention, therefore I reserve to myself the right to make such changes as fairly fall within the scope 80 thereof.

85 Having thus described my invention, I claim as new and desire to secure by Letters Patent:

90 1. A frame made from a pliable blank 90 consisting of an angular surface element having extension members protruding from its edges and each of the extension members being foldable to provide on one face of the surface element at its marginal edges an angular frame bar of approximately an inverted 95 **U**-shape in cross section, the surface element having a pair of spaced slots in proximity to two of its opposite extension members, and these extension members being provided with tongues for insertion in the slots of each pair whereby the frame bar 100 will be releasably locked to the surface element.

105 2. A frame made from a pliable blank 105 consisting of a substantially rectangular surface element having flaps protruding from its edges and each of the flaps being scored so as to be foldable to provide on one face of the surface element at its marginal edges an angular frame bar of approximately an inverted **U**-shape in cross section, the surface element having a pair of spaced slots in proximity to two of its opposite extension members, and the flaps being provided with tongues which are scored so as to be folded for insertion in the slots of each 110 pair whereby the frame bar will be releasably locked to the surface element.

115 This specification signed and witnessed 120 this 11th day of February A. D. 1919.

ARTHUR S. FORD.
